FOLDABLE SEAT AND TABLE UNIT

Rudolph G. Schneider, Houston, Tex.

Application April 30, 1958, Serial No. 50,675

Term of patent 7 years

(Cl. D33—14)

Fig. 1

Fig. 2

Fig. 3

Fig. 4

Fig. 1 is a view in perspective of a foldable seat and table unit showing my new design;

Fig. 2 is a side elevational view;

Fig. 3 is an end elevational as seen from the right of Fig. 2; and

Fig. 4 is an elevational view showing the unit folded.

I claim:

The ornamental design for a foldable seat and table unit, as shown.
